UNITED STATES PATENT OFFICE.

JOHN M. HANSEN, OF PITTSBURG, PENNSYLVANIA.

RAILWAY-CAR BOLSTER.

No. 909,588.

Specification of Letters Patent. Patented Jan. 12, 1909.

Application filed January 24, 1908. Serial No. 412,488.

To all whom it may concern:

Be it known that I, JOHN M. HANSEN, a resident of Pittsburg, in the county of Allegheny and State of Pennsylvania, have invented a new and useful Improvement in Railway-Car Bolsters; and I do hereby declare the following to be a full, clear, and exact description thereof.

This invention relates to bolsters for rail-
10 way cars, such as truck bolsters.

The object of the invention is to provide a bolster which is simple and cheap of construction and which is so designed as to effectively take care of lateral stresses due to
15 end shock as well as the vertical load.

The invention comprises a bolster constructed as herein described and claimed.

In the accompanying drawing Figure 1 is a plan view of a part of a truck bolster constructed according to my invention; Fig. 2 is a side elevation thereof; Fig. 3 is an end view of the same; Fig. 4 is a vertical section on the line 4—4 Fig. 1; Fig. 5 is a similar view on the line 5—5 Fig. 1; and Fig. 6 is a
25 similar view on the line 6—6 Fig. 1.

The main portion of the body of the bolster comprises an inverted trough-shaped member, preferably formed from a single integral plate, and having the top plate 1, which is the bottom of the inverted trough, and the two vertical or side plates 2, said trough being open at the bottom as shown. The top plate 1 forms the compression member of the bolster, and the tension members
30 are formed by suitable flanged bars, such as angle bars 4, one riveted to the free edge of each of the side plates 2, and preferably on the inner faces thereof as shown, said angle bars following the contour of the edges of
35 said side plates, and extending out to the end of the bolster. The bolster is made of greater depth at its middle so as to get sufficient strength, tapering toward the ends, and having the extreme end portions formed with
40 parallel top and bottom edges so as to give a horizontal bearing on the springs. Preferably the top line of the bolster is straight as
45 shown.

The trough shaped bolster described is
50 braced at the middle portion by the center brace 7 formed as a casting and made to fit nicely within the trough shaped body, bearing against the top plate 1 thereof, and preferably having the lower end shaped to fit
55 neatly against the angle bars 4, so that said casting practically forms a strut between the

top plate of the bolster and the horizontal legs of the angle bars 4. This casting is secured in place by suitable means, such as rivets 9 driven through the side plates 2 of
60 the bolster. Other rivets 10 are driven through the top plate of the bolster and also through the center bearing plate 11. The king-pin hole 12 extends through the center bearing plate, the top plate of the bolster 65 and the casting 7.

The ends of the bolster are stiffened by means of a casting 14 which entirely fills the end, lying between the top plate of the bolster and the horizontal legs of the angle
70 bars 4. These castings are of general box shape and provided with suitable cross webs for strengthening the same. They are secured in place by suitable countersunk rivets 16, driven through the side plates of
75 the bolster. A plate 17 is secured by rivets 18 extending through the horizontal flanges of the angle bars 4 and bottom wall of the casting 14 and forms a bearing resting on the springs. Column guides 19 are secured
80 to the side plates by rivets as shown, and side bearings 20 of any approved type are secured to the top plate 1. A brake lever fulcrum 21 is also riveted to the top plate 1.

The construction of bolster described may
85 also be adapted for a body bolster by placing the trough right side up and forming the free edges of the trough on straight lines and getting the increased depth by bowing
90 the bottom of the trough downward.

The bolster described is simple and cheap of construction, consisting mainly of three pieces, namely, the trough body member and the two tension bars 4. The bolster is
95 strong, not only as against vertical loads, but also effectively takes care of the stresses due to end shock on account of its great lateral width. It practically has no parts projecting laterally beyond the trough shaped body, so that it can be readily gotten into
100 and out of the truck.

What I claim is:

1. A railway car bolster comprising an integral plate pressed to trough form with top and side plates, and angle bars riveted
105 to the free edges of the side plates.

2. A railway car bolster comprising an integral plate pressed to trough form, the sides having their greatest depth at the central portion and adapted to be mounted in
110 the side frame and removed therefrom.

3. A railway car bolster adapted to be

mounted in the side frame and removed therefrom comprising an integral plate pressed to trough form, the sides having their greatest depth at the central portion 5 and the top being co-terminous with the sides.

4. A railway car bolster adapted to be used with diamond side frame trucks adjustable therein and removable therefrom, 10 comprising an integral plate pressed to trough form, the sides having their greatest depth at the central portion.

5. A railway car bolster comprising an integral plate pressed to trough form having top and side portions with its greatest 15 depth at its central portion, and angle bars riveted to the free edges of said side portions.

6. A railway car bolster comprising an integral plate pressed to trough form with 20 top and side plates, and angle bars riveted to the inner faces of the side plates at their free edges.

7. A railway car bolster comprising an integral plate pressed to trough form with 25 top and side plates, and angle bars riveted to the free edges of the side plates, and center and side bearings secured to the top plate of the trough.

30 8. A railway car bolster comprising an integral plate pressed to trough form with top and side plates and angle bars riveted

to the inner faces of the side plates at their free edges, a center brace fitting within said trough bearing against the top plate thereof and the angle bars secured to the free edges.

9. A railway car bolster comprising an integral plate pressed to trough form with top and side plates and angle bars riveted to the inner faces of the side plates at their 40 free edges, a center brace fitting within said trough bearing against the top plate thereof and the angle bars secured to the free edges and a center bearing plate secured to said top plate and in line with said center brace. 45

10. A railway car bolster comprising an inverted trough having top and side plates and being open at the bottom and of greatest depth at its central portion, the end portions of said bolster having horizontal top 50 and bottom faces, and castings filling the ends of said trough.

11. A railway car bolster having top and side portions of general trough shape and being open at the bottom with its greatest depth at the central portion, and having angle bars riveted to the side plates along 55 their free edges.

In testimony whereof, I the said JOHN M. HANSEN, have hereunto set my hand.

JOHN M. HANSEN.
